SEWING MACHINE WITH HOOK AND EYE ATTACHMENT

William Simpson, Handsworth, Birmingham, England, assignor to Newey Brothers Limited, a British company

Filed Jan. 16, 1962, Ser. No. 166,484

Claims priority, application Great Britain Jan. 21, 1961
6 Claims. (Cl. 112—2)

This invention is concerned with a sewing machine for sewing hook tape to garments or other articles and with an attachment for a standard sewing machine enabling the machine to sew hook tape to garments or other articles.

The hook tape comprises a row of hooks attached to a length of tape and with the wires of the bills of the hooks spaced sufficiently far apart for a sewing machine needle to pass between them. The hook tape is sewn to the garment or other article by means of a line of stitching extending lengthwise of the tape and intersecting the bills of the hooks near their outer ends. These ends of the bills are curved in the usual way so that the loops of sewing cotton or the like (hereinafter referred to for convenience as cotton) slide over the curved ends of the bills as the stitches are formed and are pulled tight beneath the ends of the bills. The hook tape is sewn to the garment or other article in an inverted position, that is with the bills of the hooks projecting below the tape and with the garment or other article disposed above the tape. The sewing machine is of the standard kind comprising a pivoted rock frame carrying a needle holder which in use carries one or more needles. Each needle advances with the tape and article after it has pierced them, and in co-operation with a feed-dog beneath the tape.

The following description and the appendent claims must be understood as relating to the sewing of hook tape to an article with the aid of a machine and by the method described in the next preceding paragraph.

Throughout the specification and claims the sewing machine, and the attachment are described for convenience as if they are in their positions of use and as from the point of view of the operator. In particular it will be noted that the tape and garment or other article are advanced by the machine towards the rear of the machine, that is in a direction away from the operator.

The principal object of the invention is to prevent the needle forming the said line of stitching from striking a hook in such a way that damage would occur. The grazing of the side of a wire by the needle does not normally lead to damage, for only when the needle strikes the top of the wire directly is there a likelihood of the needle breaking.

Other objects and advantages of the invention will become apparent as the description proceeds.

According to the present invention there is provided in or for a sewing machine a feed-dog assembly comprising a feed-dog and a hook-displacing pawl.

The invention will now be more particularly described with reference to the accompanying drawings in which:

FIGURE 1 is a side view of the device in accordance with the invention and as seen from the left, showing a guide unit for the tape, a throat plate, a feed-dog assembly, a presser foot, and a needle carrier and needles.

FIGURE 2 is a plan view of the guide unit, throat plate and feed-dog assembly shown in FIGURE 1.

FIGURE 3 is a view of the feed-dog assembly from the rear, that is from the left of FIGURES 1 and 2.

FIGURE 4 is a perspective view from above the guide unit and throat plate, from a point in front of these components and to their right, the throat plate being displaced vertically downwards from its position of use for clarity of disclosure.

FIGURE 5 is a perspective view of the feed-dog assem-

2

bly, from the same position as FIGURE 4 but to a rather larger scale,

FIGURE 6 is a longitudinal section of the feed-dog assembly to a smaller scale, substantially along the line 5—6 of FIGURE 7.

FIGURE 7 is a cross-section of the feed-dog assembly, to the same scale as FIGURE 6, substantially along the line 7—7 of FIGURE 6.

FIGURE 8 is a plan view similar to FIGURE 2 but including the presser foot, the needles, and part of a length of tape and a garment to which the tape is being sewn,

FIGURE 9 is a cross-section, to a much larger scale, of the arms of the guide unit with the hook tape, but no garment, along the line 9—9 of FIGURE 8.

FIGURE 10 is a longitudinal section, to the same scale as FIGURES 6 and 7, of the upper part of the feed-dog assembly and the throat plate, showing the relative positions of these parts and of the hook tape and needles just before the needles descend, and

FIGURE 11 is a view similar to FIGURE 10, but omitting the hook tape, and illustrating the relative positions of the feed-dog assembly and the throat plate at a later stage in the sewing cycle.

25 The guide unit, throat plate and feed-dog assembly illustrated in the accompanying drawings constitute an attachment for a sewing machine of standard construction for producing two parallel lines of stitching and which is not illustrated as it forms no part of the present invention.

30 The sewing machine is of the kind having twin needles 12 mounted in a needle carrier 13 on a vertically reciprocable needle bar 14 which is also adapted to swing backwards and forwards with the pivoted rock frame, the needles being lowered when in their forward position, 35 moved backwards, raised and moved forwards again. The needles cooperate with a presser foot 36 in the usual way. The machine also has a stationary throat plate in the base plate beneath the needle carrier, and beneath the throat plate a feed-dog which moves in a path of generally elliptical shape, rising and moving backwards a little as the needles descend, moving backwards with the lowered needles, descending as the needles rise and returning to its forward position before rising again.

40 The guide unit illustrated is mounted in the base plate of the machine in front of the throat plate, which latter replaces the standard throat plate, and the feed-dog assembly replaces the standard feed-dog, being secured in position by screws passing through the holes 15 in the bar 16 forming a rearward extension of the body of the 45 assembly.

The guide unit serves to guide the hook tape and the garment, as described below, and comprises a pair of parallel arms 17 and 18 defining between them a channel for the hook tape. The front ends of the arms are supported by a horizontal pivot rod 19 extending between shoulders 26 on a pair of axially adjustable bearings 27 externally screw-threaded and mounted in aligned screw threaded holes in a pair of spaced supporting blocks 20 projecting upwards from a plate 21 forming the base of 50 the guide unit and, when in use, flush with the base plate of the machine. A helical compression spring 22 around the rod 19 between the two arms 17 and 18 tends to retain the arms in spaced relationship, and a leaf spring 23 beneath each arm urges their free ends upwards. The 55 extent to which the free ends of the arms can rise is limited by abutment between those parts of the arms in front of the pivot rod and the plate 21. Any tendency for the arms to diverge in use is prevented by the adjustable guide blocks 24 secured to the rear of the plate by screws 60 25.

The left-hand arm 17 presents an inclined upper surface 28 leading downwards and rearwards to the sewing

area, which surface acts as a support for the garment. The corresponding surface 29 of the right-hand arm 18 is similarly inclined but is rather higher than the surface 28; this is illustrated in FIGURE 9. The left-hand arm 17 is longer than the right-hand arm 18 and has a relatively thin flange 30 which extends from the lower part of the left-hand arm across the channel towards the right-hand arm 18, terminating a short way from this arm. The righthand arm 18 has a corresponding flange 31 which is above the level of, and much narrower than, the other flange 30. A narrow gap is left between the flanges 30 and 31, and the undersurface of the narrower flange 31 is curved downwards from its free edge to form a guide for the bills of the hooks as shown in FIGURE 9 and hereinafter described. The forward end of each flange is rounded off, as shown in FIGURE 8, and extends through the gap between the pivot rod 19 and the plate 21, through which gap the hook tape passes. A sheet metal mouth assembly 32 is secured to the front faces of the blocks 20 and presents a mouth 33 through which the hook tape passes, and an upper lip 34 and a lower lip 35 to guide the tape over the front edge of the plate 21 and beneath the spring 22.

The throat plate 37 lies beneath the rearmost part of each of the arms 17 and 18. An upstanding wall 38 on the throat plate constitutes an extension of the right-hand arm 18, being aligned with this arm when the device is in use. The plate 37 is formed with two slots 39 and 40 extending the direction of material feed. The left-hand slot 39 accommodates a toothed head of the food-dog assembly, and the right-hand slot accommodates an upstanding guide forming part of this assembly, these parts being hereinafter described in detail. The left-hand arm 17 and flange 30 are formed with a slot 41 aligned with the left-hand slot 39 in the throat plate, but this flange 30 does not extend as far as the right-hand slot 40 in the throat plate. The slot 40 has an extension 42 at its forward end which extends towards the left, and the flange 30 is notched at 43 above this extension.

The feed-dog assembly, which replaces the standard feed-dog on the machine, comprises a body 45 of which the uppermost part to the left of the body, constitutes the toothed head 46 referred to above. A longitudinal slot 47 is formed in the forward part of the head for the left-hand needle. The upstanding guide 48, which projects through the slot 40, is constituted by the upper end of a finger 49 mounted on the body 45 for limited pivotal movement about an axis at the lower end of the finger and parallel with the direction of material feed. The mounting for the finger 49 comprises a pivot screw 50.

As will be clear from FIGURES 6 and 7 the body 45 has a longitudinal groove between the toothed head 46 and the finger 49. A bar or pawl support 51 is located in the groove, being pivoted at its rear end, about a horizontal axis, on a pin 52. A V-shaped spring 53, mounted on a headed pin 54 on a forward extension 55 of the body, extends into the groove and one limb thereof bears against a stop 56 on the body whilst the other limb bears against the underside of the bar 51 urging the forward end of the bar upwards. A pawl 57 integral with the bar projects upwards from the right-hand side of the bar 51, this pawl having a tapered point 58 at its forward end and a cam surface 59 below the point and nearer the rear of the machine, which surface is inclined downwardly and rearwardly of the machine. The point 58 is normally aligned with the extension 42 of the right-hand slot 40 in the throat plate and with the notch 43 in the flange 30, and the cam surface 59 engages the rear edge 60 of the slot extension as the feed-dog assembly advances the material.

The device illustrated is used in sewing hook tape to a garment with two parallel rows of stitching, the bills of the hooks being flush with one edge of the tape and the wires of the bills being spaced sufficiently to allow

one of the needles 12 to pass between them. In use the hook tape 61 is fed from a reel or other supply beneath the level of the base plate, not shown, through the mouth 33 and into the channel between the arms 17 and 18 of the guide unit. The bills 62 of the hooks 63 project on the underside of the tape and extend around the flange 30 on the left-hand arm 17. The curved parts 64 of the hooks connecting the main parts of the bills with the attachment portions pass beneath the flange 31 which thus acts as a guide. This is shown in FIGURE 9, in which figure it will also be seen that the flange 30 is cut away at 65 on its undersurface to accommodate the main parts of the bills 62. The right-hand edge of the tape 61 abuts the inner side face of the arm 18 and the garment 66 overlies the tape and is fed with its free right-hand edge abutting the same face of the arm. The tape and garment advance to the rear of the machine, in the direction indicated by the arrows 67 in FIGURES 8 and 10.

At the sewing area the aligned edges of the tape and garment abut the upstanding guide 48 which is formed with a longitudinal groove or recess 68 to accommodate the curved parts 64 of the hooks, and also the upstanding wall 38 on the throat plate. As the needles start to descend, along the line 69 in FIGURE 10, the feed-dog assembly rises, the relative positions of the parts being illustrated in FIGURE 10. The point 58 of the pawl 57 contacts the bill 62 of any hook in line with the right-hand needle and displaces it. As it rises the feed-dog assembly advances slightly towards the rear of the machine, and in performing this movement the cam surface 59 engages the edge 60 so that the pawl remains in approximately the same place although the tape is slightly advanced. Thus any bill wire which was immediately to the rear of the point 58 and in line with the needle is moved rearwards with the tape, whilst any bill wire in front of the point 58 is prevented from moving rearwards with the tape into the path of the descending needle.

Also, as the feed-dog assembly rises, the rounded upper edge of the guide 48 strikes an inclined face of the wall 38 (see FIGURE 4) deflecting the guide 48 sideways slightly, to ensure that the guide 48 is tucked in close to the bill of the hook to support the material of the tape as the needle penetrates it. This sideways movement is allowed by the pivoting of the member 49 on the screw 50.

After the needles have pierced the garment and the tape the latter are advanced by the needles and feed-dog assembly in unison. During this advance the cam action continues and the point 58 of the pawl is depressed below the level of the bills 62, as shown in FIGURE 11, so that any bill held back by the point can move forward with the tape again. The point remains thereafter out of the path of the hooks until the assembly rises again preparatory to the next descent of the needles.

The machine makes two parallel lines of stitches of equal length, the left-hand line passing to the left of the row of hooks, in the tape, and the right-hand line extending across the curved ends of the bills of the hooks with the needle passing between the wires of the bill of each hook. During the formation of each of the stitches over a bill wire the bobbin cotton, that is the cotton fed from below the base plate, forms a loop which is pulled tight by sliding over the curved part 64 of the wire concerned.

Although the foregoing description with reference to the drawings relates largely to components forming an attachment for a standard form of sewing machine it is to be understood that it is within the scope of the invention to provide a sewing machine incorporating these or analogous components initially.

I claim:

1. In a sewing machine for sewing inverted hook tape to an article and of the kind comprising a reciprocable sewing needle and needle holder supported on a pivoted rock frame, and a cooperating feed dog; a pawl assembly

comprising a hook-displacing pawl, and a pawl support, the pawl being fixedly supported by pawl support, and the said support being movably mounted on the feed dog, a stationary member in the path of the pawl assembly and engageable with the said assembly on movement of the feed dog to cause the pawl to move relatively to the feed dog and thus to displace any hook from the path of the descending needle.

2. In the sewing machine of claim 1 wherein said pawl includes a cam surface and wherein said stationary member comprises a part of the sewing machine cooperating with said cam surface to partially restrain said pawl as said feed dog moves longitudinally to advance said tape and said article so that said pawl is adapted to engage a hook wire in the path thereof to at least partially prevent the same from advancing with the tape, whereby the needle pierces the tape at a position free from a hook wire.

3. In the sewing machine of claim 2 wherein said cam surface includes a camming part cooperating with said stationary member which upon continued advance of said feed dog effects lowering of the pawl below the level of the path of said hooks.

4. In the sewing machine of claim 1 wherein said sewing machine includes a throat plate and wherein said stationary member comprises a part of said throat plate.

5. In the sewing machine of claim 2 including a guide for said hook tape comprising a rigid supporting strip-like member extending past the sewing area, said member having a free longitudinal edge whereby said member is adapted to be interposed between said tape and the bills of said hooks, said member having an opening for the passage of the needle.

6. In the sewing machine of claim 1 including a guide member pivotally fixed to said feed dog for limited rotary movement about an axis parallel to the direction of tape movement, said guide member including a guide part extending along the path of movement of said tape and said article and being engageable by said tape to guide the edge thereof into registry with the edge of said article.
